UNITED STATES PATENT OFFICE.

THOMAS LUND, OF BEVERLY, MASSACHUSETTS, ASSIGNOR TO UNITED SHOE MANUFACTORY CORPORATION, OF PATERSON, NEW JERSEY, A CORPORATION OF NEW JERSEY.

STACKING MECHANISM.

1,404,210.

Specification of Letters Patent. Patented Jan. 24, 1922.

Application filed February 16, 1918. Serial No. 217,540.

To all whom it may concern:

Be it known that I, THOMAS LUND, a citizen of the United States, residing at Beverly, in the county of Middlesex and State of Massachusetts, have invented certain Improvements in Stacking Mechanism, of which the following description, in connection with the accompanying drawings, is a specification, like reference characters on the drawings indicating like parts in the several figures.

This invention relates to mechanisms for stacking blanks to facilitate subsequent handling of the blanks and is herein illustrated with reference to stacking box toe blanks after they have been operated upon by a skiving machine.

In the manufacture of boots and shoes it is customary to skive the edges of a box toe blank preparatory to incorporating it in a boot or shoe; and for this purpose the blanks are commonly run through a suitable skiving machine of which there are various types. Commonly the skived blanks drop from the machine into a receptacle and are stacked by hand before being transferred to the operator by whom they are incorporated in a shoe.

The general object of the present invention is to provide improved means for stacking these and similar blanks.

According to one feature of the invention there is provided a holder or magazine for the blanks, and means for gripping the blanks and stacking them in parallel relation thereto. Conveniently the gripping means comprises a pair of jaws which seize the blanks firmly one by one after they have passed through the skiving or other machine and stack them in the holder, this firm gripping of the blanks greatly facilitating the accuracy with which they are placed in position.

Another feature of the invention comprises means for transferring the blanks from the machine to the stacking means. Conveniently the blanks are received one by one upon an inclined slide, a presser descends upon the blank to hold it in place, and the slide and presser are then moved in unison to place a portion of the blank between the jaws of the stacking means, whereupon the presser rises to permit the jaws to seize the blank and stack it. This transferring means ensures proper positioning of the blanks between the gripper jaws and is par-

ticularly useful when thin, light blanks upon which gravity acts feebly are being handled.

Another feature of the invention comprises a holder or magazine for the stack in the form of two parallel horizontal bars 60 upon which the blanks are suspended. This feature is particularly suitable for blanks such as box toes and counters which have one portion wider than another and readily lend themselves to a two-point suspension. 65

Referring to the accompanying drawings,

Fig. 1 is a side view, principally in elevation, of a machine in which the present invention is embodied; 70

Fig. 2 is a plan of certain parts of the machine viewed in the direction indicated by the arrow in Fig. 1, certain parts having been broken away;

Fig. 3 is a vertical transverse section 75 through the holder in which the blanks are stacked;

Fig. 4 is a longitudinal vertical section through a portion of the machine showing the parts of the stacking mechanism in one 80 position, and

Fig. 5 is a similar section showing the parts in another position which is substantially the same as is shown in Fig. 1.

The machine chosen for illustration is a 85 machine for skiving and stacking box toe blanks. The blanks, the outline of one of which is shown in dotted lines at 100 in Fig. 3, are fed one by one in any suitable manner between a feed roll 7 and a matrix roll 9, the 90 feed mechanism being timed so that each blank will be forced into the matrix. The rotating rolls then advance the blank to a skiving knife 11 which cuts off the portion of the blank projecting from the matrix, the 95 waste skiving passing up over the knife and the skived blank passing beneath it. The mechanism thus briefly outlined is old and well-known and will not be described further. 100

One purpose of the present invention is to take the blanks one by one and form them into a stack so that they may readily be handled. In the illustrative mechanism each blank falls upon an inclined slide 13; and 105 a presser 15 having teeth 16 is caused to hold the blank against the slide, as shown in Fig. 4, while the slide and presser are moved downwardly in unison. The presser is then caused to release the blank which thereupon 110

drops between the open jaws 17, 19 of a carrier. A blank is shown in this position in Fig. 5 being held suspended by contact of its edge with the upper edges of parallel bars 21 which constitute a holder or magazine for the stack of blanks (see Fig. 3). The inner ends of these bars 21 extend past the slide 13 so that each blank, as it emerges from the skiving mechanism, is guided by 10 the slide to a position of suspension upon the upper edges of the bars as shown in Fig. 5. The jaws of the carrier are closed upon the blank which is thus sustained by the blank holder, then swung rearwardly between the 15 bars 21 thus pushing the blank rearwardly along the bars, and then opened as shown in Fig. 4 and moved downwardly. After this the carrier is returned to the position shown in Fig. 5 in time to receive the next blank 20 delivered to suspended position on the bars 21.

The mechanism for causing these various movements to take place will now be described. The slide 13 is dovetailed on a stationary inclined support 23 and has formed upon it two perforated ears 25 to receive alined pins 27 on which the presser 15 is pivoted. This presser has a generally U-shaped form, as shown in Fig. 2, the arms being 25 swiveled on the pivots 27. Each arm has at its lower end a right-angled projection 115 (Figs. 4 and 5) so that in effect the arms are bell-crank levers; and to the extremities of these bell-crank levers are pivoted at 28 the 30 upper ends of connecting rods 29 the lower ends of which are provided with eyes or straps to receive two crank pins 31 on the crank shaft 33. The purpose of this construction is to raise the presser 15 if it is in 35 lowered position or to lower it if it is in raised position before upward or downward movement respectively is imparted to the slide 13. In order to ensure that the presser 15 shall in each instance be swung about the 40 axis of the pivots 27 before movement of the slide 13 takes place, a friction plug 35 (see Fig. 2) mounted in a bore in a boss 37 formed on the slide 13 is held against a guide on the slide 13 by a screw 39 which may be 45 turned to vary the pressure of the plug on the guide and thereby the force necessary to move the slide. This boss, and another like it on the opposite side of the slide, also serves a further function. After the presser 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

presser has been raised sufficiently, and thereafter by contact of the projections on tails 115 with the bosses 37 to impart upward movement to the slide 13. The support 23 and the slide 13 are cut away, as shown 70 in Fig. 2, to provide a passageway through which the upper portions of the jaws 17, 19 may pass. The presser 15 and slide 13 constitute means for transferring blanks from the machine to the carrier and are particularly useful when light blanks, such as pasteboard box toes are being handled. If heavier blanks having smooth surfaces are to be handled, the presser and slide might be dispensed with since such blanks will readily 80 slide by gravity down into place between the jaws 17, 19.

The crank shaft 33 has three crank pins (see Fig. 2) arranged in alinement and carried by crank arms. Of these crank pins 85 two serve to actuate the connecting rods 29, while the third actuates the carrier, as will now appear. This carrier, which comprises the jaws 17 and 19, is moved bodily by the middle one of the three crank pins and is 90 opened by crank arms in the form of eccentric disks 41 (see Figs. 4 and 5) which engage the jaw 17 at the proper time and move it in opposition to the force of the spring 43, these eccentric disks serving as crank arms 95 for the middle crank pin 31. The jaw 19 has a bearing on the middle crank pin 31 and is pivoted at 45 to one end of a link 47 the other end of which is pivoted at 49 (Fig. 1) to the frame of the machine. With this 100 construction the revolution of the middle crank pin 31, on which the jaw 19 is pivoted, about the axis of the crank shaft 33 imparts to the carrier the bodily motion which carries the jaws from the position shown in Fig. 5 to that shown in Fig. 4 and back again to the Fig. 5 position.

The jaw 17 is also pivoted at 45 and is moved angularly about this pivot to open the jaws at the proper times by the crank arms 110 41. These crank arms, as has been explained, are in the form of disks mounted eccentrically on the crank shaft 33 and have flattened faces 141 which permit the spring 43 to close the jaw upon the blank at the proper 115 time, the jaw 17 being comparatively wide, as shown in Fig. 2, so as to contact with the peripheries of the two disks 41.

In order to maintain the blanks of the stack in upright position as they are added 120 one by one to the stack, two catches or retainers, one of which is indicated at 51 (Fig. 1), are provided. Each catch is pivoted at 53 between upstanding lugs 55 on a cross bar 57, which rests upon the heads of screws 125 59, being held from slipping off said heads by screws 61 threaded into the heads and extending through holes in the ends of the bar. Check nuts 63, 65 may be manipulated 130 to permit the screws to be adjusted or to

lock them in any desired position. The bars 21 are pivoted on stationary rods 71 and may be adjusted angularly about said rods by a right-and-left screw 73 the head 75 of which is rotatable in a portion of the frame of the machine but held from longitudinal movement with respect thereto as shown in Fig. 3. The purpose of this adjustment is to cause the bars to contact with similar 10 points on the edges of blanks of different sizes. For example, if blanks of a given size have been operated upon and the next run of blanks is smaller, the bars 21 will be adjusted toward each other into a position 15 nearer the vertical.

By referring to Figs. 4 and 5 it will be seen that the carrier, comprising the jaws 17 and 19, not only performs the function of carrying each blank from the position 20 shown in Fig. 5 to that shown in Fig. 4, but piles the blanks in stacked relation in the holder. Referring to Fig. 4, the jaws have just delivered a blank past the retainers 51 and at the same time pushed the preceding 25 blank and the whole stack along in the holder. Upon the completion of the next cycle of operation of the carrier, the jaw 17 will have pushed the separated blank shown in Fig. 4 up against the end of the 30 stack and at the same time pushed the whole stack along in the holder. A new blank will then be in the place of the separated one which is shown.

At 76 is shown a detachable auxiliary 35 holder which is or may be substantially like the one shown in patent to Pope No. 1,088,-720 and will not be described in detail. From time to time, as it becomes filled, this auxiliary holder may be disconnected from 40 the main holder and carried, with its contents, to any desired locality.

Although the invention has been described as embodied in a particular machine adapted to handle box toe blanks, it should 45 be understood that the particular blank, which is handled, is immaterial and that the invention is not limited in the scope of its application to the particular machine which has been shown and described.

Having thus described my invention, 50 what I claim as new and desire to secure by Letters Patent of the United States is:

1. The combination with a machine for 55 acting upon blanks, of a holder for the blanks, said holder comprising a pair of bars upon the upper edges of which the blanks are received and suspended one by one as they are delivered from the operating instrumentalities of the machine, and means 60 for engaging the blanks successively while so suspended and moving them along the bars to form a stack.

2. The combination with a machine for 65 acting upon blanks, of a holder comprising parallel bars adapted to sustain the blanks

on their upper edges by contact with two points only on the edges of the blanks, said bars being located to thus receive the blanks as they are delivered from the operating instrumentalities of the machine, and means 70 operating between the bars for pushing the suspended blanks along the supporting bars and thereby forming a stack.

3. The combination with a machine for 75 acting upon blanks, of an inclined member upon which the blanks are delivered from the operating instrumentalities of the machine, a holder comprising a pair of horizontal parallel bars extending past said member, upon the upper edges of which the 80 blanks are received and suspended one by one from the inclined member, and means for engaging the blanks successively while so suspended and moving them along the bars to form a stack.

4. The combination with a machine for 85 acting upon blanks, of a holder comprising bars located to receive the blanks from the machine and adapted to sustain the blanks by contact with two substantially opposite 90 points only on the edges thereof, means for pushing the blanks along the bars to form a stack, and means for adjusting the bars so as to cause them to engage substantially 95 similar points on the edges of blanks of a different size.

5. A holder for a stack of blanks comprising a plurality of bars by which the blanks are suspended by contact of the bars with a plurality of separated points on 100 the edge of each blank, and means for simultaneously adjusting the bars to cause them to engage substantially similar points on blanks of a different size.

6. The combination with a machine for 105 acting upon blanks, of a holder for the blanks, a carrier for stacking the blanks in the holder, and means for receiving the blanks from the machine and delivering them to the carrier, said means comprising 110 a plate, a presser pivoted on the plate, means for moving the presser toward and from the plate to hold and to release the blank, and means for moving the plate and presser in unison from receiving to delivering position.

7. The combination with a machine for 115 acting upon blanks, of a holder for the blanks, an inclined support, a slide mounted on the support and arranged to receive the 120 blanks one by one from the machine, a presser for holding a blank on the slide, means for moving the presser into contact with the blank, for moving the presser and slide in unison, and for thereafter moving 125 the presser to release the blank, a carrier arranged to receive the released blank, and means for causing the carrier to stack the blank in the holder.

8. The combination with a machine for 130

acting upon blanks, of a holder for the blanks, a downwardly inclined member to which the blanks are delivered by the machine, and means including a pair of jaws for transferring the blanks from the member to the holder.

9. The combination with a machine for acting upon blanks, of a holder for the blanks, an inclined member having an opening therein, a carrier, and means for moving the carrier back and forth through the opening to stack the blanks in the holder.

10. The combination with a machine for operating upon blanks of a holder in which the blanks are stacked said holder comprising two substantially horizontal bars spaced apart a distance less than a selected dimension of a blank and adapted to suspend each blank by contact with points on the edges thereof, with the opposite extremities of the blank, considered with reference to the selected dimension, overhanging the points of suspension.

11. A holder for sustaining a stack of blanks, each of which, in plan, has at least one convex edge, comprising a two point suspension consisting of parallel bars spaced apart a distance less than the length of said convex edge on which said blanks rest with their convex edges in contact therewith.

12. A holder for sustaining a stack of blanks by their edges comprising a pair of parallel horizontal rods a fixed distance apart, a pair of vertically arranged bars one pivoted on each rod, the free edges of which act as the blank sustaining means, and means for varying the distance between said bars.

13. A machine for skiving and stacking light weight blanks having, in combination, 40 skiving mechanism, a blank holder, an in-

clined member down which the blanks tend to slide after having been skived, means for transferring the blanks to a stack in the holder, and means for insuring a delivery of the blanks to the transferring means.

45

14. A blank skiving and stacking machine having, in combination, a horizontally arranged skiving knife, means for feeding a blank horizontally to said knife and then deflecting it into a vertical position, and means for receiving the blank and stacking it while maintaining its vertical position.

50

15. A blank skiving and stacking machine having, in combination, means for feeding blanks in a horizontal plane to said skiving mechanism, means for turning the skived blanks into a vertical plane, a holder for sustaining the blanks by their edges, and means for stacking the blanks on said holder.

55

16. A blank skiving and stacking machine having, in combination, skiving mechanism, a blank holder, a downwardly inclined guide between said mechanism and holder, and rotary means for transferring the blanks from a stack in the guide to the holder.

60

17. A machine for operating upon blanks of sheet material, having in combination, skiving mechanism to which blanks may be fed one by one, a magazine in which the skived blanks are received as they are discharged from said mechanism, a pivoted stacking device, and means for swinging the device about its pivot to operate upon the blanks after they have reached the magazine to bring them into stacked relation to the other blanks therein.

70

In testimony whereof I have signed my name to this specification.

75

THOMAS LUND.
